UNITED STATES PATENT OFFICE.

PETER HARDMAN, OF WILLIMANTIC, CONNECTICUT, ASSIGNOR TO THE AMERICAN THREAD COMPANY, OF JERSEY CITY, NEW JERSEY, A CORPORATION OF NEW JERSEY.

APPARATUS FOR PRODUCING THREAD MOUNTINGS.

Application filed March 31, 1924. Serial No. 703,047.

My invention relates to thread grouping and mounting and has for its object to provide a machine for producing thread mountings to be cut up into strips for display cards, to expedite and cheapen the cost of thread grouping and mounting; to provide a machine which can be used to mount groups of a width substantially uniform, several groups being made up of threads of 5 different thickness. A further object of the invention is to produce a machine which acts to mount groups of threads upon an extended web supplied from a roll and received by a take-up. It further has for its 10 object to bring about other improvements and produce other novel and valuable results as will appear from the description as follows:

The following is a description of an embodiment of my invention, reference being had to the accompanying drawings, in which,

Fig. 1 is a right-hand diagrammatic side elevation of an apparatus embodying my 25 invention;

Fig. 2 is an enlarged left-hand view of the same with the exception of the supply roll and take-up;

Fig. 3 is a plan view of the portion shown 30 in Fig. 2;

Fig. 4 is a central vertical section on the line 4—4, Fig. 3;

Fig. 5 is an enlarged detail partially in section on line 5—5 of Fig. 2 of what I term 35 the registered roll and the parts associated therewith;

Fig. 6 is a section on the line 6—6, Fig. 2, showing enlarged details of what I term the 40 registering rolls and the associated parts;

Fig. 7 is a detail view showing a strip of paper passing through the registering rolls and being punctured thereby;

Fig. 8 is an enlarged detail of the tension, 45 selecting and spacing plates;

Fig. 9 is a section of the same on the line 9—9, Fig. 8;

Fig. 10 is an enlarged detail taken on the line 10—10, Fig. 1, showing the take-up with its friction drive;

Fig. 11 is an enlarged detail view of the preferred form of spacer bar for supplying groups of thread directly to the web;

Fig. 12 is a section of the same on the line 12—12, Fig. 11; and,

Fig. 13 is an enlarged transverse section 55 of the dauber roll.

Referring more particularly to the drawings, 2 is the main frame of the machine which carries a guide roller 4 over which a web 6 of paper such as cardboard passes 60 from a supply drum 8 to a tension device 10, this tension device being an adjustable spring clamp as shown in Figs. 2, 3 and 4, through which the web is drawn. The web 6 then passes between two rolls 12 and 14 65 shown in detail in Fig. 6, which rolls I term "registering rolls" because they are punch and die rolls for forming perforations in the edges of the web. The roll 12 is provided with punches 16 near each of its ends 70 and the roll 14 is provided with corresponding dies 18. The web contacts with the lower roll only, the two rolls being spaced apart and the upper roll serving merely as a carrier for the punches. The punches and 75 dies are spaced apart by equal angles so that the perforations in the paper are equally distant from each other.

From the registering rolls the web passes around a drum 20 which I call a "registered 80 drum", the same being provided with properly spaced pins 22 (see Fig. 5) which enter correspondingly spaced holes 24 previously formed in the edges of the web (see Fig. 3).

From the registered drum 20 the web 85 passes to a take-up mechanism which comprises a drum 26. This drum is removably mounted upon a shaft 28, which shaft is driven through a friction device by a sprocket chain 30.

This friction device shown in Fig. 10 consists of a flanged member 32 which is secured to the shaft by a set-screw, a second flange 34 and an intermediate member 36 carrying the teeth for the sprocket chain 30 95 and held between the plates 32 and 34 under yielding pressure due to the spring 38, the plate 34 being keyed to the hub of the plate 32 so as to be movable endwise.

The take-up drum 26 is removably secured 100 to the shaft 28 by a stud 40 which is mounted upon a flange 42, the head of the stud passing through the web 44 of the drum, a slot 46 with an enlarged opening at one end being provided for that purpose.

In the operation of the machine, groups of thread are supplied to and mounted upon the web 6 during its passage from the sup-

ply roll 8 to the take-up 26. For this purpose an angular creel 48 is provided adapted to carry a plurality of series of bobbins on each side. This creel is triangular in shape and provided with vertical bars 50 whose outer faces are parallel to the central axis of the triangle. This results in having the bobbins 52 properly stepped so that the thread from each bobbin will be kept separate, as shown in Fig. 3.

At the front of the creel there are brackets or plates 54, each having on both sides of its center a series of holes 56, the holes corresponding to the number of bobbins in a horizontal row of the creel as shown in Fig. 3. These holes are spaced apart by the same amount as the bobbins in each horizontal row are axially displaced. In addition, the thread from any one bobbin, with the exception of those in the first vertical rows, passes through a guide 58 mounted on the vertical bar next ahead of the bar carrying said bobbin as shown in Fig. 2. The guide for any bobbin is in a plane parallel to the medial plane of the creel and intersecting the core of the bobbin at its center. In addition to these guides, some of the vertical bars 50 have supporting arms 60 which assist in guiding the threads passing to the brackets 54. These arms are long enough to extend beneath the threads from all bobbins located to the rear thereof in any one row, and preferably have upturned ends.

The brackets 54 thus each deliver two groups of threads, one from each side. When the bobbins are properly selected and arranged, the threads in any one group are of the same size and character and by the means hereinafter described are kept together and arranged in parallel order until they are applied to and securely mounted upon the web 6.

Thus the left-hand group of threads delivered from the upper bracket 54, as shown in Fig. 4, is passed successively through the selecting, spacing and tension plates 62-64, each thread passing through separate perforations 66 and 68 shown in Fig. 8 of said plates, the threads being so passed as to not cross one another in going from the bracket 54 to the plate 62. These perforations are arranged in inclined rows, substantially parallel to one another. After passing through the plate 64 the threads pass beneath a tension rod 70 and over a tension rod 72 and thence over a spacing bar 74, which spacing bar is provided with a plurality of grooves, one groove for each group of threads. The inclination of the rows of holes 68 results in laying the threads side by side as they pass beneath the rod 70 as shown in Fig. 8. The group then passes over a tension rod 76 and beneath a spacing bar 78, which brings it in close proximity to the drum 20 carrying the paper web on which it is to be mounted.

The threads in passing through the holes in plate 64 to and beyond the spacing bar 78 have their parallelism maintained so that when they are laid upon the web they are parallel to one another and also parallel to the axis of said web, or, in other words, to the plane which is at right angles to the axis of the registered roll 20 which carries the web.

The spacing bars 74 and 78 have one side cut away. On account of this construction the spacing of the threads can be varied somewhat by adjusting these bars angularly. The thread is drawn across the corner formed by the cut away side as shown in Fig. 12. In the bar 74 the spacing notches are semi-circular. In the bar 78, however, I prefer to make them with slanting bottoms as shown somewhat exaggerated in Fig. 11, which slant is slightly decreased as the threads decrease in size. This automatically lays them closely side by side with the desired compactness in the groups. An average slant of about one thirty-second of an inch in quarter inch grooves gives satisfactory results.

Before the threads are brought into contact with the web in the manner described, the web is provided with transverse lines of glue 80, shown in Fig. 3, there being two transverse lines of glue placed quite closely together and preferably two additional lines of glue as shown, the four lines constituting a composite band of glue. These transverse lines of glue are applied by a rotary dauber 82 having four daubing arms, each of which is provided with four ridges 83, as shown on an enlarged scale in Fig. 13. This dauber receives its glue from an intermediate roll 84, which in turn receives its glue from a feed roll 86 which dips into glue within a tank 88 and is engaged by a scraper 87. The rolls 84 and 86 and scraper 87 are carried by an adjustable support. The space between the second and third ridges 83 of the dauber is preferably greater than between other adjacent ridges so as to provide ample cutting space.

The rolls 84 and 86 shown in Fig. 4 are geared together as shown in Fig. 2 and are driven by an intermediate gear 90 which meshes with a gear 92 carried by the shaft 94 of the registered drum and rotating therewith directly drives the gear 93. The dauber roller gear 95 meshes directly with and is driven by the gear 92. The shaft 94 also carries a sprocket wheel 96, which through the sprocket chains 30, drives the take-up drum 26. The gearing is such that the peripheral speeds of the drum 20, the rolls 84 and 86, and the dauber 82 are equal. The take-up drum tends to move at a slightly faster rate which causes the friction drive to slip and maintains a tension on the web.

The gear 92 also drives a pressure roll 98

through the gear 100, which roll is carried by an adjustable yoke 101 and acts to press the threads upon the web 6 after they have been applied to the glued surface thereof.

5 The dauber device is carried by an adjustable hanger which swings about the shaft 102. When this hanger is withdrawn, the dauber can be removed for cleansing. Such cleansing is necessary if the machine is allowed to remain idle for any considerable length of time. When the dauber is removed, the gear 90 can be shifted out of mesh with gear 93 and the hand wheel 97 actuated to cause the rolls 84 and 86 to revolve. These rolls under those conditions can be easily washed by removing the glue tank 88 and supplying water to the surrounding receptacle 104. This receptacle is mounted upon levers connected by the links 106-107 so that it can be raised and lowered as desired, the detent 108 engaging a notch in quadrant 109 being provided for holding it in elevated position. The link 107 is adjustable in length and is adjusted so as to bring the four points of support for the receptacle into the same plane.

10 The mechanism as a whole is driven by power supplied to the fast pulley 110 mounted upon the worm shaft 111, the worm of which engages a worm wheel 112 on the shaft 94 as shown in Fig. 2.

15 The rolls 12 and 14 shown in Fig. 6 being geared together and having punches and dies which must work in synchronism, means is provided for adjusting one relatively to the other. Thus the shaft of the roll 12 is provided with a flange 114 to which the gear 116 is held by screws 118. The gear 116 is provided with slots 120 for the screws 118 so as to permit it to be adjusted relatively to the flange 114. It is driven by the gear 92 through an intermediate gear 117, as shown in Fig. 2.

20 Somewhat similar means are provided for adjusting the registered drum 20 with relation to the rolls 12 and 14 so that the pins 22 upon the registered drum may be in proper relation to the punches and dies of the rolls 12 and 14. To accomplish this the shaft of the registered drum 20 is provided with a flange 122 having slots 124 through which adjusting screws 126 pass.

25 The left-hand portion of Fig. 3 shows a plan view of the end of the web after it has traversed the machine before described, the same consisting of the base portion 6 having the groups of threads 200 secured thereon by transverse strips of adhesive 80, the groups being of substantially the same width and the number of threads in any one group varying with their size.

30 To summarize the method carried out by the machine, a web of paper such as cardboard is supplied from a roll 8 and passes over the guide 4 through the tension device

and between the registering rolls to the registered drum 20 and thence to the take-up, which take-up, on account of its friction drive, keeps the web under tension. As the web is passing around the registered drum 20 it is supplied with transverse lines of glue by the dauber of the gluing mechanism and after being so supplied it is also supplied with substantially uniform parallel groups of parallel threads which are laid upon the web parallel to its axis. These threads are thus brought in contact with the strips of glue. They are then forced into more intimate contact therewith by the presser roll 98 so that the take-up winds up a long strip composed of parallel groups of parallel threads mounted upon a paper backing. The movement of the parts is comparatively slow and the take-up is situated quite a distance from the other parts of the machine so that the glue dries sufficiently before it is wound upon the take-up.

35 In utilizing my product I subsequently remove the take-up drum with the web wound thereon and cut the web into transverse sections by means of a cutting machine which is the subject of another application filed by me on March 31, 1924, Serial No. 703,046, forming strips which are mounted with screens to form display cards.

40 As stated, the widths of the groups of threads depend upon the size of the threads and the number of threads employed. Preferably all the groups are made of substantially the same width and in carrying out my process I therefore, where the threads are of large size, use less threads in a group than where the threads are of smaller size, as indicated at Figs. 3 and 8. This is a result which is not possible by the old methods heretofore employed in which there are an equal number of threads in all groups and the width of the groups necessarily increases as the size of the threads increases. This substantial uniformity of width of groups is an important advantage attained by my invention.

45 As will be evident to those skilled in the art, my invention permits of various modifications without departing from the spirit thereof or the scope of the appended claims.

50 What I claim is:

1. The combination of means for supplying a paper web, take-up means for said web, means situated at an intermediate point for applying to said web lines of adhesive transverse to the axis of said web, and means for subsequently applying to the web with the adhesive applied thereon groups of threads so that said threads are parallel to each other and to the line of movement of said web.

55 2. The combination of means for supplying a paper web, take-up means for said web, means situated at an intermediate point for applying to said web transverse lines of ad-

4
hesive and means for subsequently applying to the web with the adhesive applied thereon groups of threads so that said threads are parallel to each other and to the line of movement of said web, said intermediate means comprising a drum around a portion of whose periphery said web passes and a rotary dauber contacting with a portion of said web which is upon said drum, said drum and dauber being rotated in timed relation.

3. The combination of means for supplying a paper web, take-up means for said web, means situated at an intermediate point for applying to said web transverse lines of adhesive and means for subsequently applying to the web with the adhesive applied thereon groups of threads so that said threads are parallel to each other and to the line of movement of said web, said intermediate means comprising a drum around a portion of whose periphery said web passes and a dauber contacting with a portion of said web which is upon said drum, said drum and dauber being rotated in timed relation, said drum having projections adapted to enter perforations in the edges of said web.

4. The combination of means for supplying a paper web, take-up means for said web, means situated at an intermediate point for applying to said web transverse lines of adhesive and means for subsequently applying to the web with the adhesive applied thereon groups of threads so that said threads are parallel to each other and to the line of movement of said web, said intermediate means comprising a drum around a portion of whose periphery said web passes, and a dauber contacting with a portion of said web which is upon said drum, said drum and dauber being rotated in timed relation, said drum having projections adapted to enter perforations in the edges of said web, said take-up acting to maintain the web under tension after it leaves said drum.

45. 5. The combination of means for supplying a paper web, take-up means for said web, means situated at an intermediate point for applying to said web transverse lines of adhesive, and means for subsequently applying to the web with the adhesive applied thereon groups of threads so that said threads are parallel to each other and to the line of movement of said web, said intermediate means comprising a drum around a portion of whose periphery said web passes and a dauber contacting with a portion of said web which is upon said drum, said drum and dauber being rotated in timed relation, said drum having projections adapted to enter perforations in the edges of said web, said take-up comprising a take-up drum and a slip connection through which said take-up drum is driven, and acting to maintain the web under tension after it leaves said first drum.

6. The combination of means for supplying a paper web, take-up means for said web, means situated at an intermediate point for applying to said web transverse lines of adhesive and means for subsequently applying to the web with the adhesive applied thereon groups of threads so that said threads are parallel to each other and to the line of movement of said web, said intermediate means comprising a drum around a portion of whose periphery said web passes and a dauber contacting with a portion of said web which is upon said drum, said drum and dauber being rotated in timed relation, said drum having projections adapted to enter perforations in the edges of said web, in combination with means for perforating said web parallel to its edges so as to form perforations for the projections upon said drum.

7. The combination of means for supplying a paper web, take-up means for said web, means situated at an intermediate point for applying to said web transverse lines of adhesive and means for subsequently applying to the web with the adhesive applied thereon groups of threads so that said threads are parallel to each other and to the line of movement of said web, said intermediate means comprising a drum around a portion of whose periphery said web passes and a dauber contacting with a portion of said web which is upon said drum, said drum and dauber being rotated in timed relation, said drum having projections adapted to enter perforations in the edges of said web, in combination with registering rolls and means for driving said rolls synchronously with said drum.

8. The combination of means for supplying a paper web, take-up means for said web, means situated at an intermediate point for applying to said web transverse lines of adhesive and means for subsequently applying to the web with the adhesive applied thereon groups of threads so that said threads are parallel to each other and to the line of movement of said web, said intermediate means comprising a drum around a portion of whose periphery said web passes and a dauber contacting with a portion of said web which is upon said drum, said drum and dauber being rotated in timed relation, said drum having projections adapted to enter perforations in the edges of said web, in combination with registering rolls and means for driving said rolls synchronously with said drum, and a tension device acting upon said web between said registering rolls and the source of supply.

9. The combination of means for supplying a paper web, take-up means for said web, means situated at an intermediate point for applying to said web transverse lines of adhesive and subsequently applying to the web

with the adhesive applied thereon groups of threads so that said threads are parallel to each other and to the line of movement of said web, in combination with a creel adapted to deliver groups of similar threads, means for arranging said threads parallel to one another and in parallel groups, and means for maintaining such grouping and parallelism of the threads until they are applied to the web.

10. The combination of means for supplying a paper web, take-up means for said web, means situated at an intermediate point for applying to said web transverse lines of adhesive and means for subsequently applying to the web with the adhesive applied thereon groups of threads so that said threads are parallel to each other and to the line of movement of said web, in combination with a creel adapted to deliver groups of similar threads, means for arranging said threads parallel to one another and in parallel groups, and means for maintaining such grouping and parallelism of the threads until 20 they are applied to the web, and means for applying tension to said threads individually.

11. In a machine of the character described, a thread condensing guide for parallel threads having grooves the bottoms of which slant continuously from one side of the groove to the other so as to compact the threads together side by side.

12. The combination of means for supplying a paper web, take-up means for said web, means situated at an intermediate point for applying to said web transverse lines of adhesive and means for subsequently applying to the web with the adhesive applied

thereon groups of threads so that said threads are parallel to each other and to the line of movement of said web, in combination with a creel adapted to deliver groups of similar threads, means for arranging said threads parallel to one another and in parallel groups, means for maintaining such grouping and parallelism of the threads until they are applied to the web, tension means for applying tension to said threads individually, and a horizontal tension bar following said tension means, said tension means having guide openings arranged substantially in planes inclined to the axis of said tension bar.

13. In a machine of the character described, the combination of two plates located side by side, each plate having a series of holes, said series lying respectively in similarly inclined planes, and a tension bar on the delivery side of said two plates each inclined series of holes in the plate adjacent to said tension bar being spaced so as to deliver threads in close juxtaposition with one another to said bar.

14. In a machine of the character described, the combination of a tension bar and a plate substantially parallel thereto and having a series of holes, said series being inclined to the axis of said bar, said bar being adjacent to one end of the series, and means for feeding threads through said holes and around the side of the bar remote therefrom, each inclined series of holes in the plate adjacent to said tension bar being spaced so as to deliver threads in close juxtaposition with one another to said bar.

PETER HARDMAN.
